INVENTOR
Leone Lazzari
BY *W. Lee Stevens*
ATTORNEY

UNITED STATES PATENT OFFICE.

LEONE LAZZARI, OF GREENVILLE, NEW JERSEY.

VENTILATED WATERPROOF SHOE.

Application filed March 14, 1922. Serial No. 543,718.

To all whom it may concern:

Be it known that I, LEONE LAZZARI, a citizen of the United States, and a resident of Greenville, county of Hudson, and State 5 of New Jersey, have invented certain new and useful Improvements in Ventilated Waterproof Shoes.

My invention relates to means for ventilating and cushioning waterproof shoes to 10 provide maximum comfort to the wearer, and at the same time to avoid the usual ventilating apertures through the walls of the shoe which are objectionable for a number of reasons, particularly in permitting the 15 passage of moisture into the shoe. Other objects of the invention will hereinafter appear.

The invention will be understood by reference to the accompanying drawings, in 20 which—

Fig. 1 is a perspective view of a shoe embodying the improvements, with the upper 25 cut away.

Fig. 2 is a cross section on lines 2—2, Fig. 1.

Fig. 3 is a plan view of the ventilating cushion sole.

My shoe consists of the upper 1, which is secured to a welt 2 in the usual manner, and 30 the outsole 3 is attached to the welt as customary. Disposed immediately above the outsole is the ventilating cushion sole A, which may be of rubber or other flexible springy material, rubber being preferred. The ventilating sole preferably is formed with the 35 marginal flange a which is co-extensive with the outer sole 3 and thus is disposed intermediate the latter and the welt 2, being stitched thereto. However, the construction 40 and arrangement of the ventilating sole and its relation to the inner sole is such that it is securely held in position independently of the flange and stitching, so that the flange may be omitted if desired. Generally, the 45 flange is desirable because it aids in waterproofing the shoe. Disposed above the ventilating sole A is the insole 4.

From the plan view of the ventilating sole A in Fig. 3, it will be seen that it is formed 50 at certain points, with the upwardly projecting lugs or teats b, each teat being formed with a central vertical aperture b'. Referring to Fig. 2, it will be noted that the apertures b' do not pass through the venti-

lating sole, but the aperture in each case 55 merges into a lateral aperture b'' which passes through the wall of the teat and into register with a groove or channel c extending longitudinally of the ventilating sole. The said ventilating sole is formed with a 60 plurality of the longitudinal channels c, the channels merging at each end of the sole into a connecting channel d, so that air may pass from one longitudinal channel to another, via a connecting channel d (Fig. 3). 65

In the present embodiment of the invention, I have provided a series of two of the apertured lugs or teats b in such position as to be immediately below the toe arch, or first phalangeal joint, of the foot and a single apertured teat b in such position as to be 70 immediately under the central or main arch of the foot. The teats pass upwardly through suitable apertures formed in the insole and preferably lie flush with the upper surface of the latter, although if the channels c are deep and there is very substantial yield of the ventilating sole and hence depression of the insole the teats may be so proportioned that their upper surfaces will normally be somewhat below the 75 upper surface of the insole.

In the use of the shoe and when the foot descends, the pressure of the foot upon the insole will depress and partly collapse the 80 ventilating sole and air will be forced from the channel c and d, through the apertures b'' and b' in the teats and thence into the shoe above the insole. When the foot is lifted and the pressure released the ventilating sole will, through its elasticity, be 85 restored to its normal position, and air will thereby be drawn into the top of the shoe about the foot of the wearer and will pass 90 into the channels. In this manner a circulation of air through the shoe is effected and ventilation of the shoe is thus maintained. 95

As the outer sole of a shoe wears away in use and its thickness decreases, the inner sole moves downward accordingly and becomes displaced to such an extent that 100 cracks are formed in the ordinary fibre sole when the outsole is worn through or thereabouts. For this reason and because of the yielding nature of intermediate cushion 105 ventilating soles, it is practically impossible to properly ventilate a shoe through perforations in the insole placed in register

with transverse or longitudinal channels in the cushion ventilating sole. In the movement of the soles the perforations in the insole will in many cases be carried out of register with the channels and be closed by a wall of the cushion ventilating sole. This difficulty I entirely overcome by the formation of my ventilating sole and its cooperation with the insole. The passage of air 10 from the ventilating sole to above the insole and vice versa is via apertures in members which project upwardly through the insole and which lock the ventilating and insoles together against relative lateral 15 movement. These members are so positioned, beneath arches of the foot, that even should they be slightly projected above the insole, in the act of walking, they will not come into contact with the foot.

20 It will be understood that any desired number of lugs or teats may be carried by the ventilating sole, and that various modifications may be made in the embodiment of the invention shown in the drawings,

without departing from the spirit of my 25 invention.

What I claim is:

A ventilated shoe comprising an outsole, an insole formed with a plurality of apertures, and a ventilating sole of resilient material, an air chamber being formed between the latter soles and the ventilating sole being provided with teats passing into the apertures of the inner sole and extending substantially to the upper surface thereof and serving to lock the two soles against lateral movement and being formed with longitudinal apertures providing communication between the upper surface of the inner sole and the air chamber below the 35 40 said sole.

In testimony whereof, I have signed my name to this specification in the presence of two subscribing witnesses:

LEONE LAZZARI.
